SIGNORS OF ONE-THIRD TO ALICK WELLSTEAD CAPENER, OF LONDON, ENGLAND.

HORSESHOE-PAD.

1,391,655.

Specification of Letters Patent. Patented Sept. 20, 1921.

Application filed May 21, 1918. Serial No. 235,905.

(GRANTED UNDER THE PROVISIONS OF THE ACT OF MARCH 3, 1921, 41 STAT. L., 1313.)

To all whom it may concern:

Be it known that we, EDWARD SINFIELD and WILLIAM HENRY GOLDFINCH, residing at London, England, have invented certain new and useful Improvements in Horseshoe-Pads, (for which we have filed an application in England, Feb. 13, 1917, No. 2172, the final number of which application is 111,952,) of which the following is a specification.

This invention relates to improvements in elastic horse-shoe pads, of the kind known as bar-pads, which comprise a backing designed to be inserted and clamped between the shoe and the hoof, and a rubber pad which is positioned between the heels of the shoe.

The objects of our invention are, to firmly interlock the pad with the shoe, to minimize slipping, and to preserve complete ventilation and natural action of the hoof.

According to our invention an elastic bar-pad for horse-shoes comprises a rubber pad and a backing therefor, designed so as to inclose the heels of the shoe and cover the heel of the frog, and also so as to firmly interlock with the converging heel ends of the shoe. The backing is furnished with lateral extensions arranged to engage between the hoof and the inner surface of the shoe, while the pad is formed with lateral recesses for receiving the converging heel ends of the shoe, so that the intermediate part of the pad forms a wedge-like extension that firmly interlocks with such converging heel ends when applied to the shoe. The backing may be formed of leather or other material, or be formed integral with the pad, in which case either the whole backing, or part thereof only, is reinforced with canvas or other fabric. The pad body is reinforced with one or more light metal stiffeners arranged so that the ends thereof extend into the lateral recesses, flush with their bottom surfaces to form bearings for the shoe heels.

Our invention is illustrated by way of example in the accompanying drawings where-in similar reference numerals indicate like parts.

Figure 1 is a top plan view of our improved horseshoe pad the backing being partly broken away to show the reinforcement therein; Fig. 1^a is a similar view illustrating a modification in the arrange-

ment of the reinforcement; Figs. 2 and 3 are respectively underside and side views thereof; Fig. 4 is an underside view showing the application of the pad to a horse shoe; and Fig. 5 is a side view thereof.

1 indicates the rubber pad, formed with lateral recesses 2, so that the intermediate part, which fits between the converging ends of the shoe, forms a wedge-like extension 3. 4 is the pad backing provided with lateral extensions 5. 6 is a metal stiffener arranged in the body of the pad so that its ends project into the recesses 2, flush with the adjacent bottom surfaces of the latter, and afford bearings for the heel ends of the shoe. Before fixing the shoe to the hoof, the pad and shoe are assembled by pressing the same together at right angles to the tread, thus causing the converging heel ends of the shoe 7, to take into the lateral recesses 2, of the pad, so that the lateral extensions 5, of the pad backing, rest upon the inner surface of the shoe, while the wedge-like extension 3, of the pad, projects between and dovetails with the converging ends of the shoe, such shoe ends being also inclosed by the heel of the pad 1, as is clearly illustrated in Figs. 4 and 5, of the drawings, so that the pad 1, and shoe 7, are firmly interlocked against relative horizontal movements. When the assembled horseshoe and pad are secured to the hoof, the extensions 5, of the pad backing are clamped between the hoof and the shoe, and are further secured by the rear nails of the shoe which are driven through the same.

The pad backing 4, may be of leather or other material; alternatively, it may be formed integral with the pad, in which case, either the whole backing is reinforced with canvas or other fabric, indicated by 4^a, Fig. 1, which is molded therein, or part only of the integral backing, including its extensions 5, may be so reinforced, as indicated by the shaded portion and dotted line 8, in Fig. 1^a.

Our improved pad is designed so as to cover the rear portion of the frog of the hoof, as indicated at Fig. 4, the inner portion of the frog, indicated by the dotted lines 9, and the remainder of the hoof, being left uncovered so that complete ventilation and the natural action of the hoof are assured.

What we claim is:—

1. An elastic bar-pad for horseshoes, comprising a rubber pad and a backing, designed to cover the rear of the frog and to inclose the heel ends of the shoe, there being lateral extensions on said backing for engagement between the hoof and the shoe, lateral recesses in said pad for receiving the heel ends of the shoe, a wedge-like extension of the pad intermediate of said heel ends, which firmly interlocks therewith, and metal reinforcements in said pad the ends whereof extend into said lateral recesses and form bearings for the shoe heels.
- 15 2. An elastic bar-pad for horseshoes comprising a rubber pad with a reinforced integral backing designed to cover the rear of the frog and inclose the heel ends of the shoe, there being lateral extensions on said backing, lateral recesses in said pad, and an intermediate wedge-like extension adapted to

receive and interlock with the converging heel ends of the shoe, and a light metal reinforcement in said pad arranged to form bearing surfaces for the shoe heels in said lateral recesses.

- 25 3. An elastic bar-pad for horseshoes comprising a rubber pad with an integral backing reinforced with leather and designed to cover the frog portion of the hoof, and furnished with lateral extensions for engagement between the hoof and the shoe, said pad being formed with lateral recesses for receiving the converging heel ends of the shoe and extending rearwardly of said ends, a wedge-like extension of said pad positioned between and interlocking with said shoe heels, and a metal reinforcement which extends across said pad into the lateral recesses flush with the bottom surfaces thereof.
